UNITED STATES PATENT OFFICE

2,500,266

CAN OPENER

Winfred W. Weller, Likely, Calif.

Application December 10, 1948; Serial No. 64,620

2 Claims. (Cl. 30—10)

1

The present invention relates to can openers and it consists in the combinations, constructions and arrangements of parts herein described and claimed.

Generally there is provided a compact and simply constructed can opener which may be mounted in any convenient place and which, when not in use, occupies a minimum of space. There is provided a vertical base member upon which is vertically and adjustably mounted a can-supporting member. To the upper end of the base member there is pivotally connected a handle or lever which carries adjacent its inner end a can-puncturing blade which is adapted to cut a V-shaped opening in the top of a can and adjacent the edge thereof adjacent the base. There is also carried a vent punch which is adapted to form an air opening on the top of the can adjacent the edge thereof at a point opposite to the V-shaped opening.

It is, accordingly, an object of the present invention to provide a can opener which is simple and inexpensive in its construction and yet efficient and effective in use.

Another object of the invention is the provision of novel means for adjustably mounting a shelf or can-supporting member forming a part of the invention.

Another object of the invention is the provision of a novel blade and lever arrangement forming a part of the invention.

Another object of the invention is the provision of novel guide means for properly positioning a can upon the shelf aforementioned.

Other and further objects of the invention will become apparent from a reading of the following specification taken in conjunction with the drawings, in which:

Figure 1 is a side elevational view of an embodiment of the invention,

Figure 2 is a front elevational view thereof,

Figure 3 is a sectional view taken along line 3—3 of Figure 2,

Figure 4 is a fragmentary sectional view illustrating the manner of using the can opener forming the present invention;

Figure 5 is a fragmentary vertical sectional view illustrating certain details of construction,

Figure 6 is a side elevational view of the device in folded condition as it appears when not in use, and

Figures 7 to 9, inclusive, are perspective views illustrating the component parts of the invention.

Referring more particularly to the drawings, 55 juncture line with the shelf 31.

2

there is shown therein a can opener having a vertically extending generally flat base member 10 having a flange-like wall-engaging integrally formed foot 11 at its lower end and integrally formed, inwardly extending side members 12 each provided with integrally formed lower feet 13 and integrally formed upper feet 14.

Openings 15 are provided in the face of the base 10 adjacent each of the feet 13 and 14 for the reception of nails, screws or the like, as indicated at 16.

The lower portion of the base 10 is provided with a centrally disposed vertically extending panel having a plurality of upwardly directed 15 horizontally extending teeth 17 which are preferably formed integrally with the base and the base is provided at its upper end with a downwardly directed opening 18 to provide clearance for a blade hereinafter to be referred to.

20 The upper extremity of the base 10 is bent to form a pair of forwardly curled hinge members 19 to each of which is affixed a forwardly projecting guide detent 20.

An elongated handle 21 is provided with an 25 integrally formed hinge member 22 at its inner end and a pin 23 extends through the members 19 and the member 22. A can-puncturing blade 24 of triangular shape is affixed to the handle 21 and extends downwardly therefrom and at a 30 right angle thereto. The blade 24 is affixed to the handle 21 adjacent the hinge member 22. A vent punch 25 is affixed to the underside of the lever 21 in spaced relation to the blade 24.

When the blade member 10 is affixed, for example, to a wall 26 or the like, a recess 27 will be provided in such wall to accommodate the blade 24 when the lever 21 is in operative position as shown in Figure 6 and an elongated vertical passage 28 will be formed upon either side of the device between the wall 26 and the inner edges of the side walls 12 and legs 13 and 14.

An adjustable shelf is provided and consists of a vertically extending body 29 having at its upper end a pair of integrally formed, inwardly directed 45 hooks 30 which lie in the passages 28 and are vertically slidably therein. The lower end of the body 29 has integrally formed therewith a horizontally and outwardly extending shelf or platform 31 which is provided with a centrally disposed recess 32 for the reception of the lower end of the handle when the same is not in use as shown, for example, in Figure 6, and an angularly and downwardly directed dog 33 is affixed centrally upon the rear of the body 29 at its 50 juncture line with the shelf 31.

In operation, it will be apparent that a can 34 containing a liquid such as beer, fruit juices or the like may be placed upon the platform 31 and against both of the guide detents 20. The handle 21 may be then swung downwardly upon its hinge, as indicated in Figure 1, whereupon the blade 24 will puncture and cut a V-shaped opening in the top of the can adjacent the wall and the vent punch 25 will punch an air vent in the top of the can at a point adjacent the outer side thereof. The platform or shelf 31 may be vertically adjusted by simply grasping the sides of the body 29 with one's fingers and moving the same outwardly to disengage the dog 33 from the teeth 17 whereupon the shelf assembly may be moved to another position and the dog reengaged with the teeth 17 at another point. The recess 27 provides clearance for the blade 24 when the device is not in use.

While but one form of the invention has been shown and described herein, it will be readily apparent to those skilled in the art that many minor modifications may be made herein without departing from the spirit of the invention or the scope of the appended claims.

What is claimed is:

1. A device of the character described comprising a vertically extending base member, a shelf assembly, means for vertically adjusting the shelf assembly upon the base member, a lever pivotally connected with the upper end of the base member, a blade affixed to the lever and a vent punch

affixed to the lever, said means for vertically adjusting the shelf assembly including a panel of horizontally extending teeth formed in the base member and a downwardly and inwardly directed dog carried by the shelf assembly.

2. A device of the character described comprising a vertically extending base member, inwardly directed integrally formed feet for the base member, a shelf member, means for vertically adjusting the shelf member upon the base member, a lever hingedly connected to the upper end of the base, a dependant blade affixed to the lever adjacent the inner end thereof and a dependant vent punch affixed to the lever in spaced relation to the blade, said means for vertically adjusting the shelf including a plurality of horizontally extending teeth formed in the base member, a pair of vertically directed hooks carried at the upper end of the shelf assembly and slideable between the sides of the base member and the feet and a downwardly and inwardly directed dog affixed to the lower end of the shelf assembly.

WINFRED W. WELLER.
